Patented Feb. 15, 1898.

FIG. 1.

FIG. 2.

Attest,

M. P. Smith,

A. J. McCauley

Inventor:-

William Sanders.

By Higdon, Longan & Higdon Atts:

UNITED STATES PATENT OFFICE.

WILLIAM SANDERS, OF ST. LOUIS, MISSOURI.

DESIGN FOR A CHURN-DASHER.

SPECIFICATION forming part of Design No. 28,283, dated February 15, 1898.

Application filed December 14, 1897. Serial No. 661,904. Term of patent 7 years.

To all whom it may concern:

Be it known that I, WILLIAM SANDERS, of the city of St. Louis, State of Missouri, have invented a new and original Design for Churn-Dashers, of which the following is a full, clear, and exact description, reference being had to the accompanying drawings, forming a part hereof.

Figure 1 is a top plan view of a churn-dasher embodying my design; and Fig. 2 is a sectional view of the dasher, which view is taken approximately on a line 2 2 of Fig. 1.

The leading feature of my design consists of a body in the form of a truncated cone, the periphery of which body is provided with a series of continuous corrugations, which corrugations are semicircular in cross-section. Surmounting the body 1 and extending vertically upward from the diametrical center

thereof is a cylindrical body, through which 20 body and the first-mentioned body is formed a continuous bore or passage.

Referring by numerals to the drawings, 1 indicates the body, which is in the form of a truncated cone. 2 indicates corrugations 25 formed on the periphery face of said body; 3, the cylindrical body, and 4 the bore or passage that extends through bodies 1 and 3.

I claim—

The design for a churn-dasher substantially 30 as herein shown and described.

In testimony whereof I affix my signature in presence of two witnesses.

WILLIAM SANDERS.

Witnesses:

EDWARD E. LONGAN,
ALBERT J. McCUALEY.
